UNITED STATES PATENT OFFICE

2,430,406

PAJAMA TROUSERS

Lillion L. Nahas and Anna Nahas,
Beaumont, Tex.

Application August 3, 1945, Serial No. 608,706

3 Claims. (Cl. 2—83)

1

This invention relates to improvements in pajama trousers.

It is a matter of common knowledge that the legs of pajama trousers, when the wearer is reclined, will have a tendency to creep up upon the leg as an incident of the wearer moving, particularly if the wearer is restless. To avoid discomfort it becomes necessary for the wearer to sit up and pull the legs of the pajamas back into position. This, of course, constitutes a considerable inconvenience, especially during winter time when it becomes necessary to throw off blankets, covers, etc.

It is a primary purpose of this invention to provide pajama trousers with loops at the lower portions of the legs thereof so that the trousers may be readily readjusted merely by the feet of the wearer, without the necessity of sitting up in bed.

A further object of this invention is the provision of pajamas, the legs of which are provided with loops of such nature as to enable the wearer, thru his or her foot, to move the leg portions into proper position.

Other objects and advantages of the invention will be apparent from the following detailed description.

In the accompanying drawing, forming a part of this specification, and wherein similar reference characters designate corresponding parts throughout the several views,

Figure 1 is a fragmentary perspective view of pajama trousers showing the toe inserting loops of the legs of the pajamas.

Figure 2 is a fragmentary perspective view showing pajama trousers upon a wearer and one of the loops in normal position.

Fig. 3 is a fragmentary perspective view showing the manner in which a wearer may, with facility, adjust the pajama legs.

Figure 4 is a fragmentary cross sectional view taken thru the material of a pair of pajamas showing the nature of the loop formation.

In the drawing, wherein for the purpose of illustration is shown only a preferred embodiment of the invention, the letter A may generally designate a pair of pajama trousers having the leg portions 10 and 11 thereof provided with loops 12 at the lower portions thereof preferably just above the bottom hem edge 14. The loops 12 are preferably located at the inside of the leg portions 10 and 11 in position above or adjacent to the angle. The loops may be suitably hemmed at the margins thereof. They are relatively narrow and elongated and doubled at their ends, as 55

2

shown at 16 in Figure 4 of the drawing and stitched at 17 to the material of the leg. This leaves an open loop 20.

In actual use the loops will not be uncomfortable to the wearer as an incident of bulginess, since they lie between or at the insides of the legs of the wearer. The mode of adjustment is shown in Figure 3 where a wearer's foot is shown as having the toe 22 inserted thru one of the loops 12 for the purpose of adjusting the leg portion 10. The facility with which the leg portion 10 may be pushed down over the leg is obvious from Figure 3.

Various changes in the shape, size and arrangement of parts may be made to the form of invention herein shown and described, without departing from the spirit of the invention or the scope of the following claims.

We claim:

- 20 1. Pajama trousers having leg portions and loose fitting normally open toe inserting loops secured externally upon said leg portions above the bottom opening in the respective leg portions.
- 25 2. Trousers provided with leg portions having toe inserting loops externally thereof upon the insides of the leg portions adjacent to the lower ends of said leg portion.
- 30 3. Pajama trousers having leg portions each of which is provided upon the inside surfaces thereof near the bottom opening of the leg portion with a loose fitting loop, and means securing the material of each loop at its ends to its leg portion so that the intermediate portion of the loop is spaced from the leg portion to provide a normally open pocketing arrangement for receiving the toe of a wearer whereby to enable the wearer to pull down the leg portion.

Certificate of Correction

Patent No. 2,430,406.

November 4, 1947.

LILLION L. NAHAS ET AL.

It is hereby certified that error appears in the printed specification of the above numbered patent requiring correction as follows: Column 1, line 53, for the word "angle" read *ankle*; and that the said Letters Patent should be read with this correction therein that the same may conform to the record of the case in the Patent Office.

Signed and sealed this 9th day of March, A. D. 1948.
